CRIBBAGE AND CARD SCORING BOARD

Ray Robitaille and John Muggah, Detroit, Mich.

Application June 26, 1936, Serial No. 87,548

1 Claim. (Cl. 235—90)

This invention relates to cribbage and card scoring boards and has for an object to provide a score board having a plurality of concentric circular series of tally pin receiving openings, and 5 having an indicator for indicating an initial or starting point in the outermost circular series of openings, and also having guides for directing the tally pin from the end of one circular series of openings to the beginning of the next inscribed 10 circular series of openings to the end that the tally pin may be advanced progressively clockwise around the score board to finish at the center of the score board and thus eliminate the inaccurate scoring with ordinary cribbage score boards 15 in which the scorer moves the tally pin up and down a straight row of openings.

A further object is to provide a cribbage score board in which two, three or more players may score their points simultaneously, the structure 20 also including a receptacle for cigarette ashes and also including underneath the receptacle a tray having a removable bottom for storing the tally pins.

With the above and other objects in view the 25 invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a plan view of a cribbage score 35 board constructed in accordance with the invention.

Figure 2 is a longitudinal sectional view taken on the line 2—2 of Figure 1.

Figure 3 is a detail sectional view taken on the 40 line 3—3 of Figure 1.

Referring now to the drawing in which like characters of reference designate similar parts in the various views, 9 designates a board having a 45 depending marginal flange 10 which may be formed of any desired material, such as glass, for example, the board being somewhat hour-glass shape in profile, that is, it is provided with two substantially circular ends 11 and 12 which 50 are duplicates of each other, the ends being connected by a shank 13 having a depending arcuate flange 14 of greater radius than the radius of the curved ends 11 and 12. The shank is provided with a receptacle 15 for the reception 55 of cigarette ashes or other material, there being

cigar or cigarette grooves 16 formed in the top face of the shank as illustrated.

Each circular end of the board is provided on the top face with three concentric circular series of openings 17, 18, and 19, containing forty openings each, and there is an opening 20 formed at the center of the circular end of the board, all of these openings being adapted to receive a tally pin 21 which is advanced by the player progressively from a starting point on the outer 10 series of openings 17 to a finishing point at the center opening 20 to tally the game of 121 points.

An indicator 22, in the nature of an arrowhead, is applied to the surface of the board at or near the receptacle and points diametrically 15 across the circular end of the board to the edge thereof to direct the player to start his tally pin at a certain opening in the outer series of circular openings 17, which, for the purpose of clarity, has been indicated with the legend "Start" on the 20 drawing. The indicator may be applied to the 25 board in any suitable manner such as for example, by painting in color thereon.

A guide 23 is applied to the board and connects the final tally pin receiving opening of the circular series of openings 17 with the initial tally pin receiving opening of the next inscribed circular series of openings 18. Likewise, a guide 24 connects the final tally pin receiving opening of the intermediate circular series of openings 18 with the initial tally pin receiving opening of the next inscribed, or innermost circular series of tally pin receiving openings 19. These guides 23 and 24 30 may be applied to the board in any preferred manner such as, for example, by painting in contrasting colors or otherwise as desired. The 35 guides are substantially parallel and pass obliquely across a radius of the circular board, said radius passing between the initial and the final tally pin receiving opening of each circular series. The purpose of these guides is to direct the player 40 accurately from each annular series of openings to the next inscribed annular series of openings progressively until the 120th opening is arrived at.

A substantially triangular guide 25 is disposed 45 on the board with its apex at the center opening 20 and with its base contiguous to the innermost straight guide 24, said radius just mentioned being the median line of the triangular guide. The triangular guide likewise may be applied to the board in any preferred manner, as by painting, in either a contrasting color to the straight guides 23 and 24 or not. The purpose of the guide 25 is to direct the player in progressing from the final or 120th opening in 50 55

Underneath the ash receptacle the shank is provided with a tally pin tray 31 having a removable bottom 32 that is slidably fitted in a dove tail groove 33 formed in the tray as illustrated.

From the above description it is thought that the construction and operation of the invention will be fully understood without further explanation.

What is claimed is:

A score board of substantially hour-glass profile having circular ends connected by a shank, said shank having sides the radius of curvature of which is outside of the shank and of the same length as the radius of curvature of the ends, 15 the ends and the shank having a depending peripheral flange, an additional score board having an arcuate flange of the same radius of curvature as the arcuate flange of the shank and adapted to abut said flange of the shank, 20 and a U-shaped clamp adapted to straddle the shank flange and the additional board flange to clamp the additional board flange to the shank flange.
